ATTORNEYS

UNITED STATES PATENT OFFICE.

CHRISTIAN SEIDEL, OF NEW YORK, N. Y.

DESIGN FOR RUFFLING.

No. 37,647.

Specification for Design.

Patented Nov. 7, 1905.

Application filed July 20, 1905. Serial No. 270,580. Term of patent 3½ years.

To all whom it may concern:

Be it known that I, CHRISTIAN SEIDEL, a citizen of the United States, and a resident of the city of New York, borough of the Bronx, in the county and State of New York, have invented a new, original, and ornamental Design for Ruffling, reference being had to the accompanying drawing, in which the figure is a plan of a ruffling, showing my new design.

I claim—

The ornamental design for ruffling shown.
CHRISTIAN SEIDEL.
